SPRING CATCH

Donald A. Morand, Portland, Oreg.

Application June 5, 1944, Serial No. 538,723

2 Claims. (Cl. 292—128)

This invention relates generally to hardware and particularly to a spring catch.

The main object of this invention is to provide a spring catch especially adapted for use on caskets, which has an improved action in that it is smoother in operation and eliminates all banging in the closing of the casket.

The second object is to so construct the catch as to eliminate a large amount of the breakage commonly occurring in such devices.

The third object is to provide a spring catch which will be made of a minimum number of parts and will be extremely easy to assemble, and when once assembled, it will be so interlocking that it cannot be accidentally disassembled.

The fourth object is to construct a catch of the class described which will be easy to build and in which the parts are so united as to provide the maximum amount of strength with the least amount of stress on the individual members.

The fifth object is to permit the use of a narrow base plate making the device especially adaptable for thin walled and small sized caskets.

The sixth object is to avoid the delay and expense ordinarily occasioned when a catch breaks after a latch is in place.

I accomplish these and other objects in a manner set forth in the following specification as illustrated in the accompanying drawing, in which

Fig. 1 is a plan of the device.

Fig. 2 is a side elevation of Fig. 1 with a portion broken away in vertical section.

Fig. 3 is an end elevation of the device.

Fig. 4 is a fragmentary horizontal section taken along the line 4—4 in Fig. 5.

Fig. 5 is a fragmentary section taken along the line 5—5 in Fig. 4.

Similar numbers refer to similar parts throughout the several views.

Before entering into an explanation of this invention, it will be understood that these devices are used principally to hold down the covers of caskets and the main advantages arising from their construction are most apparent in connection with this class of containers, although it is obvious that they can be used for other purposes as well. The description, therefore, will be limited to the catch itself.

Referring particularly to the invention, same will be seen to consist of a base plate 10, the major portion of which is circular in form in order that it may be placed in a bored recess and having one straight edge 11, which conforms to the casket cover side. The usual counter sunk screw holes 12 are provided. In the plate 10 is

formed an opening 13 which is rectangular in form, except that one side 14 has an inturned lug 15 between the sides 16. Extending upwardly through the plate 10 is a U-shaped frame 17 whose legs 18 are somewhat wider than the distance between a side 14 and the opposite side 19.

The legs 18 are narrowed to form the shoulders 20 which engage the under side of the sides 14 of the opening 13.

Each leg 18 is divided at its upper end, one portion 21 consisting of an ear having a curved side 22, which is an arc struck from the corner 23 at the lower edge of the side 19.

The second portion of the leg 18 constitutes a standard 24 whose lower edge 25 is slightly relieved to facilitate the insertion of the legs 18 into the opening 13. The standards 24 are provided with perforations 26. The portion of the device thus far described is now assembled by inserting the legs 18 into the opening 13 with a rocking motion about the corner 23, after which the projections 21 are bent outwardly as shown in Figs. 1 to 3. It can be seen that while the edge 25 and the projections 21 prevent the frame 17 from escaping downwardly, the shoulders 20 prevent the upward movement of the frame 17 through the opening 13. It will be desirable in most instances, to permit the side 19 to extend a short distance into the edges 27 of the frame 17.

Referring now to the movable member of the device, same will be seen to consist of a hook 28 mounted on the lower end of the arm 29, which is pivotally mounted on the rivet 30 which journals in the perforations 26 in the standards 24. The head 31 of the rivet 30 is somewhat enlarged and spaced from the nearest standard 24 to receive one turn 32 of a special spring 33, whose end 34 curves over the lever 35, which is integral with the arm 29. A handle 36 of any desired shape is provided on the lever 35. The pin 30 has its end 37 flattened to complete the assembly. There is indicated in dotted lines the position of the latch plate 38, which forms no part of the present invention.

From the foregoing it will be noted that there is provided an extremely strong and yet easily operated latch, the ultimate success of which is dependent to a large measure upon the details of construction set forth in the following claims.

The end 39 of the spring 33 rests upon and is free to slide on the plate 10.

While I have thus illustrated and described my invention, it is not my desire to be limited to the precise form shown herein, and I intend to cover

such forms and modifications of the invention as fall fairly within the appended claims.

I claim:

1. In a device of the class described, the combination of a base plate having a rectangular opening formed therethrough, one side of which has an inwardly extending projection, a U-shaped frame having the open ends thereof made narrower at one point to permit the entry thereof into said rectangular opening on either side of said inturned projection, the portions of said U-shaped frame above said plate being divided to form fastening ears and standards, said fastening ears having one side curved, an arc struck from a center disposed at the lower edge of the opposite side of the hole in which the U-shaped frame is disposed, said standards having shoulders formed thereon adapted to engage the top side of said plate, a pin passing through said standards having its head spaced from the adjacent side thereof, a catch hook hinged on said rivet, said catch hook having an operating lever, a spring coiled about the spaced end of said rivet, said spring having one end thereof bearing upon said plate and the other end thereof slidably bearing upon said operating lever.

2. A spring catch of the class described having a circular base, one side of which is flattened and having a rectangular opening formed therethrough, one side of said opening being parallel

with said flattened side and provided with a projection extending into said rectangular opening, a U-shaped frame disposed on the under side of said plate and formed of flat material, the width of said frame exceeding the width of said rectangular opening in a direction normal to said flat side, a portion of each side of said frame being narrowed to permit same to occupy one side of said rectangular opening, the sides of said rectangular opening being spaced by said inturned projection, the portion of said standards contacting said inturned projection, being convexly curved on the side adjacent to said flattened base side, said convexly curved portion being bent outwardly to form a fastening means, said U-shaped frame having standards formed thereon extending above said base plate and upon the top side thereof, said standards having a rivet extending therethrough, a latch hook pivotally suspended from said rivet, a lever on said latch hook adapted to move said hook, and a coil spring wound on one end of said rivet between its head and the adjacent standard and having one end of the spring slidably engaging said base plate and having the other end of said spring slidably engaging the top side of said lever whereby a rocking movement of said lever will produce a sliding movement of said spring thereon.

DONALD A. MORAND.
